UNITED STATES PATENT OFFICE

LOUIS A. MACKLANBURG, OF OKLAHOMA CITY, OKLAHOMA

DESIGN FOR A FONT OF LETTERS AND NUMERALS

Application filed May 20, 1930. Serial No. 35,703. Term of patent 14 years.

To all whom it may concern:

Be it known that I, LOUIS A. MACKLANBURG, a citizen of the United States, residing at Oklahoma City, in the county of Oklahoma and State of Oklahoma, have invented a new, original, and ornamental Design for a Font of Letters and Numerals, as shown in the accompanying drawings and described in the following specification.

In the accompanying drawings:

Figure 1 is a plan view of the letters of the font of letters and numerals showing my design;

Figure 2 is a plan view of the numerals in the font of letters and numerals showing my design; and

Figure 3 is a cross section through the numeral 8 with the numeral face down, and taken on the line 3-3 of Figure 2.

I claim:

The ornamental design for a font of letters and numerals as shown.

LOUIS A. MACKLANBURG.
